US00D956415S

(12) **United States Design Patent** (10) **Patent No.:** **US D956,415 S**
(45) **Date of Patent:** **** Jul. 5, 2022**

(54) **WALLET**

(71) Applicants: **Thuan Tran**, Santa Clara, CA (US);
Charlie Carroll, Palo Alto, CA (US);
Binh Tran, Santa Clara, CA (US)

(72) Inventors: **Thuan Tran**, Santa Clara, CA (US);
Charlie Carroll, Palo Alto, CA (US);
Binh Tran, Santa Clara, CA (US)

(73) Assignee: **Dango Products, LLC**, Portola Valley,
CA (US)

(**) Term: **15 Years**

(21) Appl. No.: **29/754,554**

(22) Filed: **Oct. 12, 2020**

Related U.S. Application Data

(63) Continuation of application No. 29/732,095, filed on
Apr. 21, 2020, now Pat. No. Des. 934,560.

(51) **LOC (13) Cl.** **03-01**

(52) **U.S. Cl.**

USPC **D3/247**
